US00D929913S

(12) **United States Design Patent** (10) Patent No.: **US D929,913 S**
(45) Date of Patent: **** Sep. 7, 2021**

(54) **GRILLE ELEMENT**

(71) Applicant: **Oshkosh Corporation**, Oshkosh, WI (US)

(72) Inventor: **Jesse Gander**, Larsen, WI (US)

(73) Assignee: **Oshkosh Corporation**, Oshkosh, WI (US)

(**) Term: **15 Years**

(21) Appl. No.: **29/750,416**

(22) Filed: **Sep. 14, 2020**

Related U.S. Application Data

(63) Continuation of application No. 29/729,772, filed on Mar. 30, 2020, now Pat. No. Des. 898,632, which is a continuation of application No. 29/706,526, filed on Sep. 20, 2019, now Pat. No. Des. 892,002, which is a continuation of application No. 29/691,172, filed on May 14, 2019, now Pat. No. Des. 863,144, which is a continuation of application No. 29/621,906, filed on Oct. 12, 2017, now Pat. No. Des. 856,860, which is a continuation of application No. 14/612,100, filed on Feb. 2, 2015, now Pat. No. 9,829,282, which is a continuation of application No. 13/629,009, filed on Sep. 27, 2012, now Pat. No. 8,943,946, and a continuation of application No. 15/599,174, filed on (Continued)

(57) **CLAIM**

I claim the ornamental design for a grille element, as shown and described.

DESCRIPTION

FIG. 1 is a front perspective view of the claimed design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 is a second front perspective view thereof; and, FIG. 9 is a detailed front perspective view thereof. The ornamental design that is claimed is shown in solid lines in the figures. Evenly-spaced broken lines depict unclaimed environmental subject matter.

1 Claim, 9 Drawing Sheets
